PERFUME COMPOSITIONS CONTAINING ETHYL 2,4-DIOXOHEXANOATE

This invention relates to ethyl 2,4-dioxohexanoate as a component of perfume and flavored compositions i.e., as an olfactory and flavoring ingredient.

In particular, the present invention comprises the discovery that ethyl 2,4-dioxohexanoate has a high odor value and desirable blending properties so as to be useful in perfume compositions. This invention also includes the discovery that ethyl 2,4-dioxohexanoate has a flavor value for use in flavored compositions.

The application of odiferous principles to commercial compositions like soaps, cosmetics, creams, powders, and lotions involves a multitude of complex problems. For example, soaps having unpleasant and sometimes offensive odors cannot be successfully marketed without counteracting such undesirable characteristics. The magnitude of this problem is especially great since soaps are an inexpensive commodity and cannot justify the use of precious odorants. Accordingly, a major consideration in the selection of an olfactory ingredient is its economical coverage over the product's objectionable character.

To be useful as an olfactory ingredient, a compound must be fragrant and as pleasant as possible, yet not interfere with the purpose for which the final product is intended by significantly affecting factors like solubility, toxicity, color, etc. For example, soap incorporating an olfactory ingredient should desirably result in a finished product having a uniform fragrance, high odor stability and effective coverage for the unpleasant odor.

SUMMARY OF THE INVENTION

Although many fragrant compounds impart desirable odors, their use may be precluded by the fact that they are either too costly and/or interfere with the purpose for which they were intended. For this reason, many fragrant compounds are not suitable to use in compositions such as soaps, bath salts, shampoos, cosmetics, creams, lotions, etc. Ethyl 2,4-dioxohexanoate is acceptable for use in such compositions, especially since the use of the compound produces economical odor coverage.

DESCRIPTION OF THE PREFERRED EMBODIMENT

The perfume compositions comprising the present invention provide pleasing odors which can be characterized as burnt caramel, opopanax, Cassia absolute, Genet absolute, Tuberose absolute and butterscotch.

As a compound reminiscent of such odors, ethyl 2,4-dioxohexanoate is valuable for use in perfumery, especially since the compound can also be blended with other fragrances to obtain perfume compositions which have widely varying odor characteristics. For example an olfactory effective amount of ethyl 2,4-dioxohexanoate can be incorporated into any of several perfume bases to produce perfume compositions such as cosmetics, soaps, lotions, aerosols, creams, powders and the like. As used herein, the term "perfume bases" comprehends materials into which the fragrant ethyl 2,4-dioxohexanoate compound is added; and the term "olfactory effective amount" denotes that amount of ethyl 2,4-dioxohexanoate which is added to a perfume base to produce a perfume composition having a pleasing fragrance.

Suitable perfume bases include bubble bath, hair dressing, detergents, bar soaps, lotions, deodorants, sachets, cold creams and the like. Of course, the chemical composition of each perfume base varies. For example, a perfume base such as bubble bath can comprise sodium sesquicarbonate and magnesium carbonate; deodorant dusting powder can comprise talc, hexachlorophene and magnesium carbonate, and after shave lotion can comprise denatured 95 percent ethyl alcohol, hexachlorophene and diethylene glycol, monoethyl ether. These or any other perfume base can then be converted to a perfume composition by the addition thereto of an olfactory effective amount of ethyl 2,4-dioxohexanoate.

The compound, which is an oily liquid at room temperature, can be incorporated into any of several perfume bases in two basic ways. Firstly, it can be added directly to a perfume base or; secondly, it can be dissolved in an alcoholic or hydro-alcoholic solution. As used herein, the term "solution" comprehends colognes, extracts, toilet waters, after shave lotions and the like. Desirably the alcohol used in these solutions is denatured 95 percent ethyl alcohol wherein the denaturant is either (1) diethylphthalate (e.g., for perfume extracts) or (2) brucine sulfate and tert. butyl alcohol (e.g., for colognes, toilet waters, etc.). The alcohols used are of two types - with a fixative and without a fixative. Fixatives (e.g., pentadecanolide, 15-hydroxypentadecanoic acid lactone) are generally added to perfumery alcohols in order to depress the "rawness" of the alcohol odor and to hasten the maturing of the olfactory ingredient in solution.

The compound can also be mixed with other olfactory ingredients to produce perfume compositions having a variety of pleasing odors. For example, ethyl 2,4-dioxohexanoate can be mixed with methyl N-3,7-dimethyl-7-hydroxyoctyliden-anthraniolate, linalyl acetate coeur, linalyl phenyl acetate, benzyl acetate, etc. Where mixed with other olfactory ingredients, the resulting compositions can have odors like, e.g., Cassia Absolute; Tuberose Absolute and Genet Absolute.

Irrespective of whether the alcohol is fixed, the resulting solution of the olfactory ingredient is aged and then chilled. The solution is desirably aged for at least 24 hours and chilled for about 1 - 2 hours in the same container which is used for preparing the solution. A solution of deodorant colognes should preferably be aged longer, i.e., about 10 days.

The concentration of the olfactory ingredient, namely, ethyl 2,4-dioxohexanoate, varies with the particular kind of solution. For example, a perfume extract can comprise an alcohol and from about 12 percent to about 25 percent of the olfactory ingredient; and a toilet water can comprise a hydro-alcoholic solution and from about 6 to about 8 percent of the compound in from about 80 to about 85 percent alcohol. Similarly, a cologne can comprise up to about 5 percent of the olfactory ingredient in from about 75 to about 85 percent alcohol.

All solutions are generally made on weight:volume basis except cosmetic solutions (e.g., after shave lotions, deodorant colognes, etc., which are generally made on a weight:weight basis. In the former case the olfactory ingredient is added by weight and the solvent is added on a sufficient quantity (q.s.) basis. Where the solution is hydro-alcoholic, the alcohol is computed as

a percentage of the total volume and is added by volume to the established weight of the compound.

Incorporation of the olfactory ingredient into a perfume base is effected by manual stirring. Certain perfume compositions such as talc should, however, be preferably prepared with the aid of a power blender. Regardless of the blending means, sufficient mixing is necessary in order to ensure a thoroughly homogenous distribution of the olfactory ingredient into the perfume base.

Good odorant results are obtained when the olfactory effective amount of ethyl 2,4-dioxohexanoate is up to about 25 percent of the weight of the perfume composition. Excellent odorant results are obtained when the olfactory effective amount is up to about 5 percent on the same basis. For example, in bubble bath, the olfactory amount of ethyl 2,4-dioxohexanoate is suitably about 8 percent by weight. A preferred embodiment utilizes about 5 percent of the olfactory ingredient.

Where used as a flavoring ingredient, ethyl 2,4-dioxohexanoate is useful for blending with food products to provide compositions having a taste characterized as: apple, butterscotch, butter-nut, maple and maple-honey. Such flavors are of particular advantage in compositions such as confections, jams, jellies, syrups, ice cream and the like. Such compositions can contain, as the flavoring ingredient, ethyl 2,4-dioxohexanoate alone or in an admixture with other flavoring ingredients. For example, the dioxohexanoate compound can be mixed with vanillin, solid extract Foenugreek, etc., to produce a syrup which has an imitation maple flavoring.

In using ethyl 2,4-dioxohexanoate as a synthetic flavoring, an effective amount of the flavoring compound is added to a food carrier to impart a palatable flavor. The relative amount of the flavoring compound in the mixture (flavoring compound+food carrier) can be expressed as a percentage of the finished food product. The percentage varies inter alia with the particular kind of food product, taste, etc.

Ethyl 2,4-dioxohexanoate can be incorporated into many food carriers, e.g., ice cream, custard, ice milk, water ices, candy, flavor bases, cake mixes, icings, fillings, and the like.

Food palatable results are obtained when the effective amount of the flavoring compound constitutes up to about 5 percent of the weight of the food product. Excellent palatable results are obtained when the effective amount of the flavoring compound constitutes up to about 1 percent on the same basis. As noted, the flavoring compound can be used to produce other tasty food products such as table syrup, cream center candy and the like. Where the flavoring compound is utilized in a table syrup, the effective amount of the flavoring compound constitutes from about 0.1 to about 0.5 percent of the weight of the food product. Likewise, cream center candy and ice cream suitably use from about 0.5 percent of the weight of the food product. Likewise, cream center candy and ice cream suitably use from about 0.25 to about 1 percent of the flavoring compound on the same basis.

The olfactory ingredient and flavoring compound, namely, ethyl 2,4-dioxohexanoate, can be prepared by a Claisen condensation of 2-butanone and diethyl oxalate using a solution of sodium ethoxide in ethyl alcohol as the base. Preferably, the ethyl alcohol is anhydrous and has a moisture content of less than 0.15 percent

(by Karl Fischer determination) so as to produce good yields.

Ethyl 2,4-dioxohexanoate has already been described in the literature, for example, in 1906 by Otto Diels in Chem.Berichte 39, 1333. However, despite the fact that ethyl 2,4-dioxohexanoate has been known for over half a century, no one until now has recognized the unique olfactory and flavoring properties of this compound. It was accordingly most surprising to find that the fragrance of ethyl 2,4-dioxohexanoate provides not only a desirable perfume odor, but also that the compound possesses the aforementioned desirable flavoring properties.

In order to illustrate our invention the following examples are given each of which utilizes ethyl 2,4-dioxohexanoate.

The physical constants of the ethyl 2,4-dioxohexanoate used were as follows:

n_{D}^{20}	1.472
B.P.	~69°C at 0.4mm/Hg
Purity (V.P.C. analysis)	percent=91 - 98
Empirical formula	$C_8H_{12}O_4$

EXAMPLE 1

Preparation of ethyl 2,4-dioxohexanoate
236 gm of anhydrous ethyl alcohol is distilled directly into a 1,000 ml three-necked flask equipped with a fast agitator, water-cooled condenser, addition funnel, thermometer and gas-inlet/outlet tube. The reaction is

conducted under a nitrogen atmosphere. Anhydrous sodium ethoxide (68 gm) is added with agitation and the mixture refluxed for 1 hour. The mixture is then cooled to a range of 0° to 5°C whereupon a mixture of 72 gm of 2-butanone and 146 gm of diethyl oxalate is slowly added through the addition funnel over a 30 minute period and under a nitrogen atmosphere at 0° to 5°C. The resulting mixture was then further cooled and agitated for 3 hours at 0° to 5°C.

After cooling to 0°C, 168 ml of a 1:1 hydrochloric acid/H₂O (6M) solution was added and the temperature of the resultant solution was maintained below 10°C. The acidified solution was extracted twice, each time with 300 ml of toluene. The organic phase was then successively washed twice with 600 ml water, once with 600 ml of a 10 percent Na₂CO₃ solution and once with 400 ml of a saturated sodium chloride solution. The toluene layers were then separated from the aqueous layers, combined, dried over magnesium sulfate and filtered. The toluene was removed by distillation under 25 mm/Hg pressure yielding ethyl 2,4-dioxohexanoate. Purity (V.P.C.) about 91 percent. Optional and further purification was effected by fractional distillation through a 6 inch glass Helix packed column at 0.2 mm/Hg. Distillation yielded:

Fract.	Vapor	Pot.	Pressure
1.	80°-85°C	95°-104°C	2.0 mm
2.	85°C	104°C	2.0 mm
3.	86°C	112°C	2.0 mm
4.	89°C	122°C	2.0 mm
5.	85°C	165°C	2.0 mm

Vapor phase chromatography (V.P.C.) analysis (125°C/SE - 30) showed Fract. 1 to be the desired product plus a small amount of unreacted diethyl oxalate. Fracts. 2-4 were shown to be 97 - 99 percent of the desired product and were accordingly combined to give a fraction of about 98 percent pure ethyl 2,4-dioxohexanoate. Fract. 5 was shown to contain the de-

sired product plus about 5 - 6 percent of unknown by-product.

EXAMPLE 2

Preparation of Imitation Maple Flavoring

An imitation maple syrup containing the following ingredients

Ingredients	Amount
methyl cyclopentenolene	15 g
vanillin	50 g
gum balsam peru	5 g
alcohol 190°	375 ml
solid extract Foenugreek	125 g
caramel coloring	185 g
ethyl 2,4-dioxohexanoate	40 g
water	q.s.
	1,000 ml

was prepared by:

1. combining the first seven ingredients above, and
2. bringing the solution up to a final volume of 1,000 ml. with water (q.s.).

EXAMPLE 3

Preparation of Cassia Absolute Perfume Composition

A perfume composition containing the following ingredients and having a Cassia absolute odor

Ingredients	Amount
n-nonyl aldehyde	560 ml
methyl n-nonyl acetaldehyde	392 ml
anisic aldehyde	280 ml
anisyl aldehyde	280 ml
benzyl alcohol (P.G.)*	2240 ml
citronellol extra	168 ml
cuminic aldehyde	56 ml
dipropylene glycol	148 ml
methyl 2-octynoate	560 ml
geraniol	560 ml
geranyl butyrate	392 ml
ethyl 2,4-dioxohexanoate 10%	500 ml
benzopyrrole(indol) 10% in triethanolamine	280 ml
2-nonenal — pure 1%	112 ml
beta-ionone	560 ml
hydroxycitronellal	1120 ml
linalool coeur	280 ml
methyl salicylate(syn)	560 ml
p-methyl acetophenone, 10%	112 ml
styrax soluble resin	560 ml
terpineol extra	280 ml

* P.G. — perfume grade

was prepared (10,000 ml) by:

1. combining the ingredients in the order as above listed, and
2. adequately mixing each ingredient into the resulting mixture in order to ensure a homogenous dispersion of each ingredient.

EXAMPLE 4

Preparation of Tuberose Absolute Perfume Composition

A perfume composition containing the following ingredients and having a Tuberose absolute odor

Ingredients	Amount
methyl n-nonyl acetaldehyde	70 ml
gamma-nonalactone	420 ml
amyl cinnamic aldehyde	280 ml
Aurantiol **	5720 ml
balsam tolu soluble resin	70 ml
benzoin siam soluble resin	70 ml
benzyl acetate	700 ml
benzyl salicylate	700 ml
celery seed oil	70 ml
folione	70 ml
ethyl 2,4-dioxohexanoate, 10%	500 ml
indolene, 10%	42 ml

iso eugenol extra	154 ml
methyl benzoate	350 ml
methyl salicylate (syn)	364 ml
methyl tuberate	28 ml
vanilla soluble odo resin	42 ml
Ylang bourbon extra	350 ml

5 ** Methyl N-3,7-dimethyl-7-hydroxyoctyliden-anthraniolate

was prepared (10,000 ml) by:

1. combining the ingredients in the order as above listed, and
2. adequately mixing each ingredient into the resulting mixture in order to ensure a homogenous dispersion of each ingredient.

EXAMPLE 5

Preparation of Genet Absolute Perfume Composition

A perfume composition containing the following ingredients and having a Genet absolute odor

Ingredients	Amount
benzo pyrone (coumarin) extra	16 ml
oranger crystals ethyl β -naphthyl	11 ml
ketone	
lauryl acetate	1 ml
n-nonyl aldehyde, 10% in	11 ml
dipropylene glycol	
n-decyl aldehyde	11 ml
n-decyl alcohol	3 ml
Anisic Aldehyde	5 ml
Aurantiol 50	3 ml
Benzyl Alcohol P.G.*	415 ml
Constituants 15	29 ml
P-cuminic aldehyde, 10% in	5 ml
dipropylene glycol	
ethyl phenyl acetate	5 ml
ethyl propionate	5 ml
folione 1% in dipropylene glycol	
geraniol	3 ml
ethyl 2,4-dioxohexanoate	10 ml
indol	10 ml
iso eugenol	52 ml
Labdanum soluble resin	52 ml
laurine extra	52 ml
linalyl acetate coeur	6 ml
linalyl phenyl acetate	52 ml
methyl aceto phenone	10 ml
Peru balsam soluble resin	124 ml
phenyl ethyl alcohol extra	21 ml
vetivert (E.I.)	83 ml

* Perfume grade

was prepared (1,000 ml) by:

1. combining the ingredients in the order as above listed, and
2. adequately mixing each ingredient into the resulting mixture in order to ensure a homogenous dispersion of each ingredient.

EXAMPLE 6

Preparation of Scented Bar Soap

A scented bar soap composition is produced by incorporating the perfume composition prepared in Example 5 into soap chips in the following manner so that the finished product contains about 1 percent, by weight, of said perfume composition:

1. weigh soap chips and transfer into mixing container (percent of perfume composition is based on total weight of chips used),
2. weigh perfume composition and premix with a small amount of soap chips,
3. combine premix with chips in container and mix until homogeneous,
4. pass chips through a worm-screw driver,
5. place ground chips into a die press and compress to a pressure of about 6,000 P.S.I., and
6. remove compressed cake and cut into quarters.

EXAMPLE 7

Preparation of Scented Bath Salts

A scented bath salts composition is produced by incorporating ethyl 2,4-dioxohexanoate into the following ingredients in the following manner so that the finished composition contains about 5 percent, by weight, of the dioxohexanoate compound:

Ingredients	Amount (%)
sodium sesquicarbonate	90
magnesium carbonate	5
ethyl 2,4-dioxohexanoate	5

was prepared by:

1. grinding the ethyl 2,4-dioxohexanoate into the magnesium carbonate in a milling apparatus,
2. adding the perfumed magnesium carbonate to the

sodium sesquicarbonate in a powder mixing apparatus, and

3. mixing the resulting mixture until the powders are thoroughly dispersed.

5 We claim:

1. A method of enhancing the odor characteristics of cosmetic compositions comprising incorporating into a cosmetic composition an olfactory effective amount of ethyl 2,4-dioxohexanoate.

10 2. The method of claim 1 wherein the said cosmetic composition is a perfume containing a mixture of different perfume ingredients other than ethyl 2,4-dioxohexanoate.

15 3. The method of claim 1 wherein said cosmetic composition is a bath salt.

* * * * *
